Attest:

UNITED STATES PATENT OFFICE.

ISAAC GOODSPED, OF NORWICH, CONNECTICUT, ASSIGNOR TO HIMSELF,
A. A. GOODSPED, E. S. STEBBINS, AND A. NEWBURY.

IMPROVED CORK-CUTTING MACHINE.

Specification forming part of Letters Patent No. 40,444, dated October 27, 1863.

To all whom it may concern:

Be it known that I, ISAAC GOODSPED, of Norwich, in the county of New London and State of Connecticut, have invented certain new and useful Improvements in Machinery for Cutting Corks for Bottles and other purposes; and I do hereby declare that the following is a full, clear, and exact description of the same, reference being had to the accompanying drawings, forming part of this specification, in which—

Figure 1 is a front view of a cork-cutting machine, illustrating my improvements. Fig. 2 is a central horizontal vertical section of the same. Fig. 3 is a transverse section of the same in the plane indicated by the line x x in Figs. 1 and 2. Fig. 4 is an inside face view of one of the cutters. Fig. 5 is an end view of the same. Figs. 6 and 7 illustrate the adaptation of the machine to the cutting of ring or shell corks.

Similar letters of reference indicate corresponding parts in the several figures.

This invention relates to cork-cutting machines in which patterns are used to determine the size and form of the corks, as described in the specification of Letters Patent granted to A. A. Goodspeed, E. S. Stebbins, and myself, dated June 4, 1861.

It consists, first, in a novel system of clamps applied to confine the knives to the pattern, whereby a single pattern only is required in cutting any one form of cork, instead of two, as described in the above-mentioned specification of Letters Patent, and much trouble is saved in adjusting the machine to cut various kinds of corks; and it consists, secondly, in so combining with each other the back spindle, which holds the slab up to the pattern in the cutting operation, and a slide which works upon the rotating spindle and has the cutters attached to it by means of a lever controlled by suitable stops upon the back spindle that a pressure upon the said lever in one direction will both cause the back spindle to hold the slab up to the pattern and drive or feed the cutters into the slab, and a pressure upon the said lever in the opposite direction will first draw back the back spindle and then draw back the cutters.

To enable others skilled in the art to make

and use my invention, I will proceed to describe its construction and operation.

A is a bed-plate, on which are the two head-stocks, B and C, one of which contains the bearings for the rotating cutter-spindle D, and the other supports the back spindle, E, which only has a longitudinal movement. The rotating cutter-spindle D has firmly secured upon it a pulley, F, for the reception of a driving-belt, through which it receives rotary motion, and a disk, G, for carrying the clamps by which the cutters J J are clamped to the pattern I; and it has fitted to it in such a manner as to slide longitudinally a disk, A, to which the heads of the cutters J J are attached, and it has the pattern I secured to the end next the back spindle. The pattern I represented is of conical form, but it may be changed for one of cylindrical of any size, or for a larger or smaller one of conical form, according to the form and size of the corks to be cut, as it regulates the size as well as the form of the corks. It is secured to the end of the spindle D concentric with it by any suitable means that will compel it to rotate with the said spindle.

The cutters J J, of which there may be one or more, but of which there are two represented in the drawings, are made of long pieces of steel plate curved transversely in the form of arcs of circles, and their cutting-edges are at the ends next the back spindle, E. The radii of the arcs of their inner faces should correspond nearly with the radii of the circles of the corks to be cut, and hence two or more cutters or sets of cutters of different sizes will be necessary for a machine to cut corks of greatly-varying sizes, though one cutter or set of cutters will serve to cut corks varying considerably in size. The disk H, to which the heads of the cutters are attached, is bored out cylindrically to fit easily and slide upon a cylindrical portion of the shaft, and to the face of this disk there are securely bolted by bolts c c radially-arranged plates K K, at the inner ends of which there are tongues which enter longitudinal grooves c' c' in the shaft for the purpose of compelling the said disk to turn with the shaft, but yet permit it to slide longitudinally thereon. The said plates are made with protuberances d d large enough to be drilled ra-

dially to the axis of the shaft and tapped for the reception of screw-pins *e e*, which, by entering the holes *f f* provided in the cutters near the heads thereof, attach the cutters to the disk *H*, the said holes and pin permitting the heads of the cutters to come in contact with the plates *K K*, that the said plates may press directly upon the cutters to force them into the slabs of cork-wood *S* to cut the cork therefrom. The cutters pass freely through openings *g g* in the disk *G* and fit into slight longitudinal grooves provided in the pattern and the spindle *D*.

L L are the clamps for securing the cutters to the pattern, made in the form of portions of a longitudinally - divided cylinder to fit, or nearly fit, the exterior surfaces of the cutters, and pivoted by pins *h h* at the middle of their length to the ends of levers *M M*, which are attached by fulcrum-pins *i i* to strong studs *N N*, which are rigidly secured in the disk *G*. At their other ends the levers *M M* are fitted with set-screws *j j*, which, by being screwed down upon the studs *N N*, are made to set the clamps down upon the cutters, and so caused to confine them to the surface of the pattern, but yet not to hold them so tightly as to prevent them from sliding along the face thereof in the cutting operation. The said clamps being arranged exactly opposite to the pattern and pivoted at the middle of their length to the levers, are enabled to adapt themselves to the form of the pattern and keep the cutters in contact with the whole length thereof, and so set them either parallel with or at the required obliquity to the axis of the rotating shaft as may be required by the form of the corks to be cut, the holes *f f* in the heads of the cutters fitting the screw-pins *e e* so loosely as to permit the cutters to freely assume the requisite position. By this mode of applying the clamps the single pattern is rendered sufficient for guiding the cutter in cutting any one kind of cork.

P is the lever for producing the longitudinal movements of the back spindle, *E*, and of the cutters. This lever has its lower end pivoted by a pin, *k*, to a collar, *l*, that is fast on a sliding rod, *Q*, which is arranged parallel with and below the spindles *D E* in guides in the head-stocks *B C*. The said lever has provided in it an opening through which the back spindle, *E*, passes, and on opposite sides of the opening there are longitudinal slots *m* for the reception of a pin, *n*, which is inserted transversely through the back spindle, the said pin serving to connect the latter spindle with the lever. The rod *Q* is connected with the hub of the disk *H* by means of an arm, *R*, which is rigidly secured to the said rod, but which is furnished at the upper end with a yoke fitting within a groove in the said hub in such manner as not to interfere with the rotation of the disk *H* and cutter-spindle. The said rod is fitted in front and behind the head-stock *C* with two stop-collars, *p* and *q*, to limit its longitudinal movement, and the back

spindle, *E*, is fitted in front and back of the said collars *r* and *s* to limit its longitudinal movement.

When rotary motion is communicated to cutter-spindle *D*, the disks *G H*, the cutters, clamps, and pattern all rotate with it. Before the slab of cork-wood *S* can be introduced between the pattern and the back spindle the upper end of the lever *P* is taken hold of by the operator and moved to the right, by which means the back spindle, *E*, is drawn back till its stop *r* comes in contact with the head-stock *C*, after which the continued movement of the lever moves the rod *Q* to the left till its stop *q* comes in contact with the head-stock *C*, and the said rod is thus caused to draw back the disk *H* and the cutters until the points or cutting-edges of the latter are brought over the pattern, as shown in Fig. 1. The slab *S* is then placed between the pattern and the back spindle, and by moving the upper end of the lever to the left the back spindle is first brought forward and caused to clamp the slab against the end of the pattern, as shown in Fig. 1, and then the rod *Q* is moved to the right, causing the disk *H* and the cutters to move in the same direction upon the cutter-spindle, the latter spindle having no longitudinal movement. This movement of the cutters presses them into the slab and feeds them as they cut thereinto by their rotary motion until they have cut through the slab, which is made known by the stop *p* coming in contact with the head-stock *C* and stopping the further movement of the rod *Q*. The pins *e e* are relieved of strain in the above operation by the plates *K K* coming in contact with heads of the cutters. The stops *s* and *p* should be so set as to limit the longitudinal movements of the spindle *E* and rod *Q* in such a manner that the edges of the cutters cannot be pressed against the end of the back spindle and be thereby injured. When the cutters have cut through the cork, the upper end of the lever is moved to the right, and after having drawn back the spindle *E* till the stop *r* comes against the head-stock *C*, it, by its action on the rod *Q*, draws back the disk *H* and withdraws the cutters from the slab, leaving the cork *t*, Fig. 2, free to be pushed out when the slab has been removed from the pattern.

Fig. 6 is an end view of the pattern and the knives for cutting a ring-shaped or shell cork, the cutter *u*, nearest the axis of the rotating spindle, making a circular cut, (represented by the smaller circle in Fig. 7,) and the cutter *v*, farthest from the axis, making a circular cut, (represented by the larger circle in the same figure.) *w*, Fig. 7, represents the ring-shaped or shell cork, being the piece which comes out of the slab between the two circular cuts, and *y* represents the smaller solid cork cut from the interior of the shell-cork.

What I claim as my invention, and desire to secure by Letters Patent, is—

1. The clamps *L L*, arranged on pivots *h h*,

and applied to the rotating and sliding cutters directly opposite to the pattern, substantially as and for the purpose herein specified.

2. Combining the clamps with the disk G or its equivalent by means of levers M, studs N, and set-screws *j j*, substantially as and for the purpose herein specified.

3. Combining the back spindle, E, with the disk or slide H, with which the cutters are

connected by means of a lever, P, whose operation is so controlled by stops as to operate the said spindle and the said disk or slide, substantially in the manner herein specified.

ISAAC GOODSPEED.
